UNITED STATES PATENT OFFICE

2,588,805

CRATE FOR BOTTLES AND LIKE CONTAINERS

Reginald Jack Cross, Gravesend, England, assignor of one-half to Essex Aero Limited, Gravesend, England

Application February 29, 1948, Serial No. 12,181
In Great Britain December 5, 1947

1 Claim. (Cl. 220—21)

1

The invention has reference to crates for bottles and like containers, for example such as are described in the specification of my copending United States application Serial No. 725,099, now abandoned, the object of the invention being to provide additional means for preventing noise due to the vibration of the bottles in the crates or arising from the impact of bottles dropped into the same.

In a crate according to the invention the floor upon which the bottles rest is perforated at the centre of each bottle-receiving compartment, and a member of a suitable resilient material is secured in the edge of each such perforation, in such fashion that the face of such member projects above the upper surface of the floor to constitute a resilient buffer or seat upon which a bottle may rest.

While the resilient members could be made solid, they are conveniently annular and in most cases the perforations in the floor-plate will be circular.

The resilient annulae are conveniently made of indiarubber, synthetic rubber, felt, leather or other material having appropriate shock-absorbing or vibration-damping qualities. Indiarubber or synthetic rubber are thought to be most suitable for this purpose, owing to their durability and capability of withstanding repeated shocks and severe wear conditions, apart from the ease with which they may be cleansed from adhering dirt by dipping in water or sluicing with a hose.

One embodiment of the invention is illustrated in and hereinafter described with reference to the accompanying drawings, of which Fig. 1 is a plan of a crate (empty) and Fig. 2 a vertical section taken on the line II—II of Fig. 1. Fig. 3 is a fragmentary view similar to Fig. 2, of a modified form of crate, taken in section along the line III—III of Fig. 4, which is an end elevation.

The construction of the crate is generally similar to that which forms the subject of United States application Serial No. 725,099. It comprises a floor-plate 10, which is flanged along its rectangular borders to constitute a frame 11 to which the corner-members 12, 12 and the fluted side-members 13, 13 are riveted at their lower extremities. The upper ends of the members 12 and 13 are riveted to an upper frame 14 of the same shape as, but slightly longer than, the frame 11. The upper frame 14 is bridged centrally by a square-section member 15; this member 15 and the end-parts of the frame 14 are shaped at 16 so as to form handles.

The crate is subdivided into a number of 55

2

bottle-receiving compartments by an apertured plate 17, mounted parallel to the floor-plate 10 at or about half the depth of the crate and riveted along its marginal flange 171 to the members 12 and 13. At each aperture 18 of the plate 17 the metal is swaged downwardly to form a lip 181. At each position on the floor-plate 10 which lies axially beneath an aperture 18, the floor-plate is dished to form an upwardly extending frusto-conical boss 101 which, where the bottles have a concave base as in the case of the bottle illustrated in Fig. 2, enters the concavity thereof and thereby serves to locate the bottle and restrain it from lateral movement in its compartment.

The frusto-conical bosses 101 are centrally perforated, at 102, and in each such perforation there is mounted a resilient annulus. This may consist of an indiarubber grommet 19 having on its external periphery a deep circumferential groove 191 of a width substantially equal to the gauge of the base-plate 10. Such an annulus 19 may be pressed into position in the perforation 102, in such manner that the inwardly directed flange which surrounds the perforation 102, is received in the said peripheral groove of the grommet, in the manner shown in Fig. 2, whereby the latter is adequately sustained in the desired position and held against dislodgment in normal conditions of use. The grommet 19 is of such thickness that the portion thereof which protrudes above the upper surface of the boss 101 is sufficiently thick to raise a bottle completely out of contact with the base-plate.

35 Apart from the function of the grommets 19 in resiliently supporting the bottles and deadening noise, it is found that the natural stickiness of the indiarubber of which they are made affords a further valuable advantage inasmuch as 40 their consequent tendency to adhere slightly to glass assists in maintaining the bottles in place even when the crate is carried in an inclined position, using one of the end-parts of the frame 14 as a handle.

45 It will also be seen from Fig. 2 that the crates may be so designed to suit the particular bottles for which they are intended to be used, that when two or more crates are stacked one upon the other, the tops of the bottles are resiliently contacted by the grommets 19 in the next upper crate, thus affording an additional preventive against lateral movement of the bottles in their compartments. In such an arrangement the bottles are in fact supported in a floating condition between upper and lower grommets, any

slight variation in the overall lengths of the bottles being allowed for by the resilience of the grommets; it is accordingly possible, if desired, to effect a considerable reduction in the depth of the crate, as illustrated in Figs. 3 and 4, with a consequent valuable economy in weight of the material employed in its construction, thereby reducing both the cost of the crate and the volume occupied in transport in the empty state.

What I claim as my invention and desire to 10 secure by Letters Patent is:

A bottle crate comprising a framework of vertical and horizontal members, a floor supported on said framework, and means dividing the interior of said crate into a plurality of compartments for individual bottles, said floor being formed to provide a general plane slightly narrower and shorter than said framework and slightly below the lower edges of said framework and adapted to project downwardly into the next 15 lower crate when stacked, the floor being dished upwardly in each compartment, and a plurality of perforations in said floor, one centrally of each said compartment, and a resilient grommet in each said perforation, said grommet being fixedly 20 secured to the inwardly directed edge of said perforation and extending above and below the said edge, the lower portion of said grommet ter-

minating within said dished portion, the height of said crate being substantially that of the bottles to be accommodated, whereby the tops of the bottles in a lower crate may engage the bottoms of the grommets of a higher crate when stacked.

REGINALD JACK CROSS.
